FACSIMILE SIGNALING SYSTEM

Charles J. Young, Princeton, N. J., assignor to
Radio Corporation of America, a corporation
of Delaware

Application December 8, 1943, Serial No. 513,373

10 Claims. (Cl. 178—6.6)

The present invention relates to facsimile signaling systems and more particularly to a receiving and recording system for producing records in facsimile from a phase modulated carrier.

If a carrier is phase modulated with image signals representing a picture, object, or other subject matter, the shade of black is represented by a shift of carrier phase of a given number of degrees from a zero position for each shade. Detection cannot be accomplished, as with a sound phase modulated signal, by an inertia detector which centers on the average frequency because the image signal has a zero frequency component. In facsimile work, it is necessary to provide means for representing or obtaining this zero frequency component at the receiver. Moreover, it is at times necessary to be able to hold a black or white condition at the recorder for relatively long periods, which can be done only if a fixed reference is provided.

In facsimile systems where faithful shade representations are to be made, a fixed reference point for the zero phase state must be available at the receiver from which to effect the control. The present invention has for its principal aim that of providing for such a zero phase reference point in a way which will be more stable than can be provided by any ordinary oscillator.

To accomplish this, the synchronizing frequency usually required for facsimile transmission, is used to provide a zero phase reference point. Preferably, the synchronizing frequency to be employed in this manner is one which is transmitted over the communication circuit along with the image signals. This transmission may be a direct wire line transmission or transmission over a radio channel.

The primary object of the present invention, therefore, is to provide a novel system for producing improved facsimile records from a phase modulated image signal.

Another object of the present invention is to employ a synchronizing signal in a novel manner to provide a reference frequency for a facsimile recording operation.

Still another object of the present invention is to operate a facsimile recorder in accordance with an image signal derived from a phase modulated carrier and a substantially constant reference frequency.

A still further object of the present invention is to provide a novel method of recording image signals representing a picture, object, or other subject matter, which comprises the utilization of a synchronizing signal as a reference frequency

with which the phase of the image signal is constantly compared during the recording process.

Other objects of the invention will become apparent when the following specification and claims are read in connection with the accompanying drawings, wherein:

Fig. 1 shows schematically a transmitting station for originating phase modulated image signals;

Fig. 2 shows schematically a facsimile receiving station which operates in accordance with the invention to record signals;

Figs. 3 to 10 inclusive are explanatory diagrammatic curves; and

Fig. 11 shows a slightly modified receiving station.

Referring to Fig. 1, there is shown a facsimile scanner or the like indicated generally by reference character 10. This scanner may be of any desired type but, for purposes of illustration, is shown as comprising a copy holding drum 12 and a facsimile signal generating scanning head 14 propelled axially along the drum by a lead screw 16. For slow speed scanning any suitable change speed device 17 may, if desired, be used to connect the drive shaft 18 of a driving motor 24 with the drive shaft 22 of the scanner. For example, gearing or a friction drive wheel may be employed. A gear and pinion combination 23 drives the lead screw 16 at the proper relative speed so that closely spaced helical scanning lines are obtained as the scanning head 14 moves axially of the drum 12.

The motor 24 is preferably a variable speed motor such as an induction motor and is connected to a suitable power source 26. The motor may be caused to operate at the desired definite scanning speed by employing the synchronizing arrangement disclosed in the copending application of Maurice Artzt, Serial No. 504,337, filed September 30, 1943, modified with respect to the transmission of the synchronizing signal as disclosed hereinafter, if desired.

In this synchronizing arrangement, briefly, synchronization is accomplished by producing a square wave representative of the speed of the apparatus to be synchronized by means of an induction generator 28. This output is supplied to the limiting amplifier 31, and the resulting wave is compared with a square wave representative of the desired scanning speed which is representative of the output from a limiter amplifier 32, which has been energized by the output (multiplied, if desired) from a closely controlled standard frequency source 33. These two waves, when beat

together in a combining network or mesh 36, produce a square wave having a characteristic, the value of which is proportional to the phase difference between these two square waves. This beat frequency wave is employed to energize an electric brake 38 mechanically connected to the driving motor 21, or to a moving part of the scanner 10. This synchronizing arrangement depends for its operation upon phase comparison of two control waves. One of these is the frequency produced by the generator 28, when the scanner 10 is operated at desired scanning speed, which is compared with a wave of like frequency. Therefore, to produce the desired wave, a frequency multiplier 39 is frequently employed to 15 change the frequency of the output from the standard source 33 to that of the generator 28 so that the comparison can be made.

The signal output from the scanning head 14, which varies in value in accordance with the shades of black and white of the copy on the cylinder 12 as it is scanned is employed to phase modulate a suitable subcarrier derived from a frequency multiplier 42. The multiplier 42 is connected to the standard frequency source 33 over conductors 45 so that the frequency thereof remains constant. The modulator 43 may be of any desired type which shifts the phase of the carrier output from the multiplier 42 in accordance with image signals from the pickup or scanning head 14. A suitable modulator for this purpose is shown in Patent No. 2,081,577, granted to Murray G. Crosby on May 25, 1937.

The phase modulated carrier from the modulator 43 is fed to a modulator or mixer 46 along with a receiver synchronizing wave of standard frequency from the standard frequency source 33. This synchronizing wave is conveyed to the mixer over conductors 48. The output connection 47 from the mixer 46 may be fed directly into any desired communication channel such as a wire line or carrier channel. For purposes of illustration, the carried channel is shown as being provided by a modulator and radio transmitter 49.

The receiving station shown on Fig. 2, which operates in accordance with the invention, comprises a radio receiver 52 of any well known type which will demodulate the carrier from the modulator and radio transmitter 49. The output of the receiver 52, appearing in the circuit 53, is divided into its two original components by any known means which may, for example, be a high pass filter 54 and a band pass filter or tuner 56. It will be understood that if wire line transmission is desired, the connection 47 at the transmitting station of Fig. 1 may be connected to the circuit 53 by a wire line path. Also, if 46 is a modulator, the arrangement of Fig. 11 will be used.

A facsimile recorder shown schematically at 59 may be of any kind such, for example, as the carbon paper recorder shown in my Patent No. Re. 20,152, granted on October 27, 1936, or alternatively, it may be of the electro-chemical or photographic type which are each well known. The drive shaft 62 for the recorder or any other mechanically moving part is provided with a brake 60 which may be similar to the brake 38 on the scanner 10 of Fig. 1. A frequency comparing device 64, which may be similar to the limiting amplifiers 31, 32, and the network 36 of Fig. 1, is connected to a generator or the like in the recorder 59 over conductors 66. The generator in the recorder (while not shown for con-

venience of illustration) may be an inductor generator like the generator 28, associated with the scanner 10. The synchronizing tone applied in Fig. 1 to the mixer 46 is separated by the tone signal separator or tuner 56 and is multiplied in a frequency multiplier 68. This frequency multiplied synchronizing tone is also applied to the frequency comparison device 64 over conductors 71. The brake 60 is connected in series with a suitable power source (not shown) connected at terminals 74 by way of conductors 76 and 77.

It will be seen from the foregoing that the recorder driving and synchronizing arrangement is similar to the driving and speed controlling arrangement for the scanner 10 of Fig. 1 of the drawings.

As pointed out previously, a definite reference frequency is to be provided, in accordance with the invention, for deriving image signals suitable for the operation of the recorder 59. This is accomplished by using the output from the standard frequency source 33 at the transmitter which is multiplied in frequency by the frequency multiplier 68 after transmission and separation. The wave shape of this frequency multiplied signal is modified to square wave form in a limiting amplifier 78 and the phase modulated signal wave obtained by demodulation in the receiver 52, after separation by the high pass filter 54, is limited and squared in a limiting amplifier 82.

Figs. 3 to 6 of the drawings will be referred to in explaining the operation of the arrangement which is provided for obtaining the derived signal. The curves of Figs. 3 to 10 are illustrative only and are not intended to represent exact values to scale, although the general wave form closely resembles that occurring in operation. In Fig. 3, the wave 84 represents the stable frequency which is obtained from the output of the frequency multiplier 68. The wave 86 represents the phase modulated subcarrier appearing in the input of the limiter amplifier 82. Assuming that the scanner 10 and modulator 43 of Fig. 1 are so arranged that the shade of black in the original copy is represented by a shift of the carrier phase of a different number of degrees from zero position for each shade, the curve of Fig. 3 represents the phase relationship between the phase modulated subcarrier 86 and the stable frequency 84 when a mid-grey portion of the original copy is being scanned.

After passing through the limiting amplifiers 78 and 82, the waves 84 and 86 respectively are as indicated by reference characters 88 and 89. The wave 88 is derived from the sine wave 84, and the wave 89 is derived from the sine wave 86. In normal operation, the frequency of these waves is equal, but the phase relationship between them may, and will, vary in accordance with the dark and light portions of the original subject which is being scanned by the scanner 10. The square wave of comparison voltage 88 is applied across a resistor 92, and the square wave of voltage 89 is applied across a resistor 93. The common terminal of the resistors 92 and 93 is coupled to a control electrode 96 of a vacuum tube 97 through a coupling condenser 98. A resistor 99 serves as a grid resistor for the tube 97. The resulting beat frequency voltage 101 of Fig. 5 is repeated and amplified by the amplifier 97.

This amplified voltage is applied to a full-wave rectifier 102 by way of a coupling transformer 75 103 and the rectified voltage 106 of Fig. 6 is

applied to a recorder amplifier 107 across a rectifier load resistor 108.

Solely by way of example and not intended as limiting the invention, the following frequency values may be employed: The standard frequency source 33 may provide a wave having an accurately maintained frequency of 200 cycles. The frequency multiplier 68 of Fig. 2 may multiply this frequency by ten so that a 2,000 cycle wave is available for synchronizing the recorder and for providing the constant frequency wave 84 of Fig. 3. In Fig. 1, the generator 28 may provide a frequency of 2,000 cycles in which case the frequency multiplier 38 will multiply the standard frequency output by ten. The multiplier 42 in this example provides a frequency of 2,000 cycles.

It will be understood that these values may be varied and that means other than those shown may be employed for synchronizing the equipment. The arrangement shown in the Patent No. 2,325,028, granted to Maurice Artzt, July 27, 1943, is suitable for the purpose. The wave 84 may be generated locally at the receiver, but, as pointed out above, this is preferably derived from the synchronizing signal which is received from the transmitter.

The wave 106 will record an image having a dot pattern and therefore, where fine picture detail is desired, the waves 84 and 86 should have a high frequency.

The output from the amplifier 107 may be modified to give an amplitude varying wave in the manner disclosed and claimed in the co-pending application of Gordon L. Fredendall, Serial No. 488,969, filed May 29, 1943.

Referring to Figs. 7 to 10, a condition is shown where a very light grey or almost white portion of the original copy is being scanned. The waves 84 and 86 in this case are almost 180° out of phase, and the resulting wave 106 shown in Fig. 10 comprises pulses of shorter time duration than the pulses exhibited by the wave 106 of Fig. 6 under the mid-grey scanning conditions. It is believed that the relationship between the curves of Figs. 3 to 6 and Figs. 7 to 10 will be fully understandable without further explanation in view of the foregoing complete description of the invention.

Fig. 11 of the drawings shows a slightly modified arrangement of the receiving equipment of Fig. 2 which will be employed to receive signals from the transmitter of Fig. 1 when the device indicated by reference character 46 functions as a modulator to amplitude modulate the already phase modulated subcarrier by the synchronizing frequency from the frequency standard 33 applied over conductors 48. The signal appearing in the conductors 53 shown on both Figs. 2 and 11 is fed directly to the limiter amplifier 82 which removes the synchronizing signal appearing as an amplitude modulation of the phase modulated carrier and shapes the phase modulated wave in a manner previously explained before it is applied to the resistor 93.

The synchronizing signal is recovered in an amplitude detector 56a, which may be of any well known type, for example, a full wave rectifier. The output in the form of an alternating current from the detector 56a is multiplied in the multiplier 68, it and the remaining apparatus being unchanged. This alternating current may be employed in the manner previously explained for synchronizing the receiver and as a reference frequency.

Various modifications of the system shown and described herein by way of example are possible, without departing from the spirit and scope of the invention described herein, and it is desired that any and all of such modifications be considered within the purview of the present invention defined by the hereinafter appended claims.

Having now described the invention, what is claimed and desired to be secured by Letters Patent is the following:

1. A facsimile receiving system for obtaining a record from a carrier, the phase of which is shifted in accordance with image signals, comprising means to compare the phase of said carrier from cycle to cycle with a synchronizing alternating voltage to derive another alternating voltage equal in frequency to said synchronizing voltage but having a wave form varying in accordance with the phase of said carrier, means to convert said derived alternating voltage into pulses, the time duration of which varies in accordance with the phase of said carrier, a recorder having a recording element, and means to cause operation of said recording element from said pulses.

2. A facsimile receiving system in which the received signals are a fixed reference frequency carried on a subcarrier which is phase modulated with facsimile signals, said carrier having a mean frequency integrally related to said reference frequency, a recorder, means at said recorder for comparing the phase of the two frequencies and obtaining from this comparison image recording currents proportional to the phase difference, and means for synchronizing said recorder by controlling its speed from the reference frequency.

3. A facsimile system comprising a facsimile transmitter and a facsimile recorder, means at said transmitter for transmitting a fixed reference frequency along with image signals carried on a phase modulated subcarrier having a mean frequency integrally related to said reference frequency, means in said recorder for comparing the phase of the two frequencies and obtaining from this comparison image recording currents proportional to the phase difference, and means for synchronizing said transmitter and recorder with each other by controlling the speed of both from the common reference frequency.

4. A facsimile system comprising a transmitter and a receiver, means for generating a synchronizing frequency, means for generating a carrier controlled by said synchronizing frequency, means at said transmitter for generating an image signal, means for shifting the phase of said carrier in accordance with successive values of said image signal, means for utilizing said synchronizing frequency for controlling the speed of said transmitter, means for transmitting said phase modulated carrier along with said synchronizing frequency to said receiver, means at said receiver for separating said synchronizing frequency and employing it to synchronize said receiver with said transmitter, means at said receiver controlled by said synchronizing frequency for generating a frequency equal to the frequency of said carrier, means to derive signals representing the phase difference between said phase modulated carrier and said locally generated frequency, means to rectify said derived signals, and means to apply said rectified signals to obtain a record.

5. In facsimile apparatus wherein image signals representative of the optical values of a transmitted image are received as phase modula-

tions of a carrier and wherein a synchronizing signal is continuously received along with said carrier, means for generating square wave signals from said received carrier, means for generating square wave signals from said synchronizing signal but equal in frequency to said carrier, means for developing a series of square wave pulses representative of the phase relationship of the combined square wave synchronizing signal and the square wave carrier signal, and means for utilizing said developed square wave pulses for obtaining a facsimile recording.

6. A facsimile receiving system comprising a recorder and in which received signals are a fixed reference frequency carried on a subcarrier which is phase modulated with facsimile signals, said carrier having a mean frequency integrally related to said reference frequency, means at said recorder for converting said reference frequency to square-wave form, means for converting said phase modulated carrier to square-wave form, means for comparing the phase of the two frequencies of square-wave form and obtaining from this comparison image recording impulses proportional to the phase difference, means for synchronizing said recorder by controlling its speed from the reference frequency.

7. A facsimile system comprising a transmitter and a receiver, means for generating a synchronizing wave, means for generating a carrier controlled by said synchronizing wave, means at said transmitter for generating an image signal, means for shifting the phase of said carrier in accordance with successive values of said image signal, means for utilizing said synchronizing wave for controlling the speed of said transmitter, means for transmitting said pulse modulated carrier along with said synchronizing wave to said receiver, means at said receiver for separating said synchronizing wave and employing it to synchronize said receiver with said transmitter, means at said receiver controlled by said synchronizing wave for generating a frequency of square wave-form equal to the frequency of said carrier, means for converting said carrier to square wave-form, means to derive impulse signals representing the phase difference between

said phase modulated carrier of square wave-form and said locally generated frequency of square wave-form, means to rectify said derived signals, and means to apply said rectified signals to obtain a record.

5 8. A facsimile receiving system in which the received signals are a synchronizing signal carried on a subcarrier which is phase modulated with facsimile signals, a facsimile recorder, means for separating the synchronizing signal, means associated with said recorder for generating signals indicative of the speed and phase of said recorder, means for comparing the phase of said synchronizing signal and said generated signal to obtain a synchronizing voltage, and means for synchronizing said recorder by controlling its speed from the synchronizing voltage.

10 9. A facsimile receiving system in which the received facsimile signals appear as a phase modulation of a carrier comprising a recorder, means for obtaining a wave having a frequency equal to the frequency of the carrier and representing the desired synchronizing speed of said recorder, means for comparing the carrier and the wave which represents the synchronizing speed of said recorder, means for developing square topped pulses representative of the comparison, and means for utilizing the pulses in said recorder to obtain reproduction of an image.

15 10. A facsimile receiving system in which the facsimile signals appear as a phase modulation of a carrier comprising a recorder, means for obtaining a wave having a frequency equal in frequency to the frequency of the carrier and representing the desired synchronizing speed of said recorder, means for converting said wave to square wave form, means for converting said carrier to square wave form, means for comparing the carrier in its square wave form and the frequency which represents the synchronizing speed of the recorder also in square wave form, means for developing square topped pulses representative of the comparison, and means for utilizing the pulses in said recorder to obtain a reproduction of said image.
